Howson & Howson

UNITED STATES PATENT OFFICE.

HARRY E. ASBURY, OF PHILADELPHIA, PENNSYLVANIA.

HAND-GRENADE.

1,311,739.

Specification of Letters Patent. Patented July 29, 1919.

Application filed May 9, 1916. Serial No. 96,336.

To all whom it may concern:

Be it known that I, HARRY E. ASBURY, a citizen of the United States, residing in Philadelphia, Pennsylvania, have invented 5 certain Improvements in Hand-Grenades, of which the following is a specification.

My invention relates to hand grenades, and consists of certain improvements in the structures forming the subject of my pending applications, filed February 18, 1916, 10 Serial Numbers 79,139 and 79,140. In the form of grenades illustrated and described in said applications, means are provided for cocking a plurality of latches controlling 15 the operation of a firing pin, preliminary to the release of said firing pin by the displacement of the latches. Under ordinary circumstances, the grenade must be thrown after the latches have been cocked since, 20 otherwise, it is necessary to hold the cocking member in latch-retaining position to support the firing pin in the inactive position.

The object of my present invention is to provide means for maintaining the cocking 25 or releasing member in latch-retaining position after the latches have been cocked, should it be unnecessary or undesirable to throw the grenade. For this purpose I provide a locking-pin for engagement with the 30 cocking member, which locking-pin in turn is held in the locking position by a safety pin; said locking-pin and the safety retaining pin being readily releasable when the grenade is to be thrown.

These and other features of my invention 35 are more fully described hereinafter, reference being had to the accompanying drawings, in which:

Figure 1, is a view in elevation partly in 40 section, of a hand grenade, showing locking means for holding the externally operable cocking member in the normal safety position when it is not desired to hurl the grenade;

Fig. 2, is a sectional view showing the 45 locking device in the inactive position and the cocking member and firing pin holding latches released, and

Fig. 3, is a sectional view on the line 50 III—III, Fig. 1, illustrating the position of the locking pin and the safety retaining pin therefor with respect to the screw plug closing the end of the grenade shell.

The grenade is of the same or substantially the same character as that illustrated 55 in my pending application before referred

to, comprising a shell 1 made of cast metal, iron for instance, which may be scored or grooved externally; some of said scores or grooves being indicated at 2, so that upon 60 bursting due to the explosion of contained material, the shell will separate into a number of fragments.

Within the shell a casing 6 is mounted, having a chamber 7 for the reception of a 65 firing pin 8 to which motion may be transmitted by a coiled spring 9 when said firing pin is released; such spring being normally compressed and held in the compressed condition with the firing pin by means herein- 70 after described.

Adjacent the casing 6 is a casing 10 forming a tubular chamber 11, which contains a detonating cap 12, while below the chamber 7 of said casing is an anvil member 13. At 75 the rear end of the grenade shell, I provide a shoulder 15 for the reception of a disk-like member or plate 16, which is apertured for the passage of said casing 6; the latter being spun over the wall of the aperture, as 80 indicated at 17. In addition, the plate 16 carries the casing 10, which may be secured to the plate 16 in the same manner as the casing 6. The plate 16 may be held in place by a screw plug 18 against which the anvil 85 13 also abuts. The construction of the anvil receiving the cap and the manner of securing the time fuse therein with a venting washer 14 is similar to and may be exactly like the arrangement disclosed in my pending application, filed February 18, 1916, Serial 90 No. 79,140.

At the opposite end of the grenade shell, a shoulder 30 is provided, and seated on this shoulder is a cupped member 31 having a 95 tubular flange 32 threaded at 33 into the upper end of the casing 6 and between which and a shoulder 34 on the firing pin 8, the coiled spring 9 is confined. Mounted on top of the cupped member is a disk or plate 100 35, which is held in position and confined in place by a screw cap or plug 36 closing the end of the shell.

The upper end of the firing pin 8 is provided with a shouldered head 37, and, as indicated in the drawings, this head is engaged by supporting members or latches 38 of a peculiar shape, which are disposed in slots 39 formed in the plate 35; each of said latches having a foot 40 adapted to engage 110 the head of the firing pin, and a shoulder 41 resting upon said disk or plate 35.

Centrally disposed with respect to the closing plug 36 is an externally operable releasing or cocking member 45 which may be manually movable in one direction; being movable in the opposite direction by means of a coiled spring 46 interposed between the same (fitting a recessed portion 47 thereof,) and the disk or plate 35.

In my present arrangement, the cocking member 45 is seated in the plug 36, and is provided with a shoulder or flange 48 to prevent displacement and limit its outward movement. This cocking member may have its outer surface partially roughened and substantially flush with the contour of said plug 36, and it is provided with an inwardly projecting portion 49 which, when the cocking member is normally disposed in the inward position, spreads or separates the latches 38 supporting the firing pin 8. The cocking member 45 is maintained in this position by means of a locking-pin 50 having a head 51 engaging the flange 48 of the cocking member; which flange may be grooved at 52 to accommodate said head. The locking-pin 50 is preferably mounted in a boss 53, formed on top of the screw plug 36, and it may be held in the locking position by the engagement of the groove 52 of the flange 48 with its head 51, against the tension of a spring 54.

The locking-pin 50 is preferably maintained in the flange-engaging position whereby the firing mechanism of the grenade is held in a "safety" condition, by a safety retaining pin 55 which passes through the plug 36 closing the end of the grenade. When it is desired to hurl the grenade, the safety retaining pin 55 is removed; the finger of the operator being maintained upon the end of the cocking member 45 so as to hold its inwardly projecting portion 49 in the latch-engaging position, and slight depression or movement of said cocking member against the pressure of the spring 46 will relieve the head 51 of the locking-pin 50 from the groove 52, and said pin 50 will be moved outwardly by its spring 54.

The latches 38, however, are still held in their separated position, maintaining the firing pin 8 out of action, by the inwardly projecting portion 49 of the cocking member 45. Upon hurling the grenade, however, the spring 46 will force the cocking member outwardly, thereby releasing the latches 38, which, in turn, release the firing pin 8; whereupon said firing pin will be forcibly moved by the spring 9 into contact with the primary firing cap, as fully described in my pending applications above referred to.

If, for any reason, it should be unnecessary to hurl the grenade, it is only necessary to press in the locking-pin 50 so as to bring its head 51 into flange-engaging position, and restore the safety retaining pin 55 to

the position illustrated in Figs. 1 and 3; thereby maintaining the inwardly projecting portion 49 of the cocking member in the latch-spreading or separating position.

The locking-pin 50 and its spring 54 are preferably mounted in a little thimble or sleeve 56 adapted to a socket 57 in the boss 53 of the screw plug 36. In forming this socket the arched wall of the screw plug 36 is preferably pierced as clearly shown in Figs. 1 and 2, and by slightly peening over the inner end of the thimble, as indicated at 58, said thimble may be firmly held in place.

It will be understood, of course, that other suitable means of holding this locking-pin in operative position may be employed; the essential thing being provision whereby it may engage and temporarily hold the cocking member in the latch retaining position and shaped to accommodate the safety retaining pin which holds said locking-pin with its head 51 in engagement with the flange 48 of said cocking member.

As this application possesses matter in common with an application filed by me March 16, 1916, Serial No. 84,600, it is to be treated as a continuation of said prior application as far as the common subject-matter is concerned.

I claim:

1. The combination with an explosive shell such as a hand grenade and explosive means within such shell, of a cocking device manually movable in the end of the shell and comprising a shouldered member having inwardly and outwardly projecting portions; said cocking device being designed for outward movement to release parts controlling the firing of the explosive means, and radially movable retaining means carried by the shell and movable in the wall of and manually operable from the exterior of the same to engage the shoulder of the cocking device; said retaining means being movable at right angles to the line of movement of the cocking device and holding the latter to maintain said explosive firing parts inactive when in engagement with its shoulder.

2. The combination with an explosive shell such as a hand grenade, explosive means within said shell and a firing pin to act upon said explosive means, of a plurality of latches for normally supporting the firing pin in the inactive position, a cocking device movable in the end of the shell and comprising a shouldered member having an inwardly projecting portion to separate said latches; said cocking device being designed to release the latches upon outward movement thereof, and a retaining member carried by the shell and movable in the wall of the same for engaging the shoulder of the cocking device; said retaining member being manually operable from the exterior of the shell and holding said cocking device by en-

- means within said shell, of a cocking device comprising a shouldered member having a portion projecting beyond said shell; said cocking device being designed for outward movement to release parts controlling the firing of the explosive means, and means for holding said cocking device in the inward position to maintain said fire-controlling parts inactive; said cocking device being inwardly movable to release its holding means.
12. The combination with an explosive shell such as a hand grenade and explosive means within said shell, of a cocking device comprising a shouldered member having a manually operable portion projecting beyond said shell; said cocking device being designed for outward movement to release parts controlling the firing of the explosive means, and a releasable pin for holding said cocking device in the inward position to maintain said fire-controlling parts inactive; said cocking device being inwardly movable to free said releasable pin therefrom.
13. The combination with an explosive shell comprising a hollow body and explosive means within the same, of a cocking device comprising a shouldered member having a portion projecting beyond said shell; said cocking device being designed for outward movement to release parts controlling the firing of the explosive means, and a pin for engagement with the shoulder of the cocking device to hold the same in the inward position to maintain said fire-controlling parts inactive; said cocking device being inwardly movable to release said pin therefrom.
14. The combination with an explosive shell comprising a hollow body and explosive means within the same, of a firing pin, a cocking device comprising a shouldered member having a portion projecting beyond said shell and an inwardly projecting portion for engagement with means for supporting said firing pin in the inactive position, said cocking device being designed for outward movement to release the parts controlling the position of the firing pin, and releasable means for engagement with the shoulder of the cocking device to hold the same in the inward position whereby the firing pin may be held in the inactive position; said cocking device being inwardly movable to free said releasable means from the shoulder thereof.
15. The combination with an explosive shell comprising a hollow body having explosive means within the same, of a firing pin, a cocking device comprising a shouldered member having a portion projecting outwardly beyond said shell; said cocking device being designed for outward movement to release parts supporting the firing pin of the explosive means; the shoulder of said cocking device being grooved, a pin having a head engaging the groove of said shoulder to hold the cocking device in engagement with the firing pin supports, and displacing means for said pin operable upon further slight inward movement of the cocking device.
16. The combination with an explosive shell comprising a hollow body having explosive means within the same and a firing pin therefor, of a cocking device comprising a shouldered member having a portion projecting outwardly beyond said shell; said cocking device being designed for outward movement to release parts supporting the firing pin of the explosive means; the shoulder of said cocking device being grooved, a safety locking pin having a head engaging said grooved shoulder to hold the cocking device in engagement with the firing pin supports, a spring for displacing said safety locking pin upon further slight inward movement of the cocking device, and a spring for moving said cocking device outward to release the firing pin supporting means and render said firing pin active.
17. The combination with an explosive shell comprising a hollow body and explosive means within the same, of a cocking device comprising a shouldered member having a portion projecting beyond said shell; said cocking device being designed for outward movement to release parts controlling the firing of the explosive means, a pin for engagement with the shoulder of the cocking device to hold the same in the inward position to maintain said firing parts inactive, a spring for displacing said pin, a thimble or shell for holding the pin and spring, and means for holding said thimble in position in the wall of the explosive shell.
